UNITED STATES PATENT OFFICE.

FREDERICK WEHINGER, OF WATERBURY, CONNECTICUT, ASSIGNOR TO WATERBURY, CLOCK CO., OF WATERBURY, CONNECTICUT, A CORPORATION.

CHIME CLOCK.

Application filed December 2, 1922. Serial No. 604,479.

To all whom it may concern:

Be it known that I, FREDERICK WEHINGER, a citizen of the United States, residing at Waterbury, in the county of New Haven 5 and State of Connecticut, have invented a new and useful Improvement in Chime Clocks; and I do hereby declare the following, when taken in connection with the accompanying drawings and the characters 10 of reference marked thereon, to be a full, clear, and exact description of the same, and which said drawings constitute part of this application and represent, in—

Fig. 1 a left-hand edge view of one form 15 which a chime clock embodying my invention may assume, the time-train being entirely omitted for the sake of clarity, with the exception of the center arbor, on which is mounted the star-wheel employed for the 20 periodic release of the chime-and-strike-trains by the time-train. In this view, the chime-and-time-trains are shown as out of synchronization, the chime-train being in the 25 position which calls for chiming the full hour, while the star-wheel, representing the time-train, is in the position which calls for the chiming of the first quarter-hour.

Fig. 2 a similar view of the clock in front elevation.

Fig. 3 a view corresponding to Fig. 2, 30 showing the synchronization of the chime-and-strike-trains, the chime-train having been warned and about to be released for chiming the full hour.

Fig. 4 a detached perspective view of the chime-correcting unit.

Fig. 5 a detached plan view of the spring friction-washer employed with the said unit.

Fig. 6 a perspective view of the star-wheel.

Fig. 7 a detached plan view of the lifting-lever of the lock-work of the chime mechanism.

It is well known that chime clocks are 45 constantly giving trouble, due to the failure, for one cause or another, of their chime-and-time-trains to synchronize. Among the causes which destroy such coordination, the setting forward and the setting 50 backward of the hands or pointers are, perhaps, the commonest, though such clocks often have the synchronization of their chime-and-time-mechanisms dislocated by the failure to wind them seasonably, thus permitting their time-mechanisms to continue

to operate after their chime-mechanisms, which require more power, have stopped. Thus, chime clocks often become a source of great inconvenience and confusion, due to the failure of their mechanisms to synchronize, although their mechanisms as mechanisms, may each function perfectly. Much ingenuity and effort have been expended in attempts to overcome the difficulties above recited. 60

My present invention relates to an improvement in chime clocks of the particular type shown and described in my prior Patent, No. 1,406,511, dated February 14, 1922, and characterized by the employment 70 of a frictionally-controlled, chime-correcting unit moved into its guard-position for preventing the chime from sounding by the chime-train, and into its clearance position under the control of the time-train and held 75 by friction in its respective positions.

My present invention has for its object the production of a chime clock of the type and specific character described, at a reduced cost, without sacrificing accuracy of 80 performance.

With this end in view, my invention consists in a chime clock characterized by having a frictionally-controlled, chime-correcting unit of "lock-work" and comprising a 85 rocking arbor mounted in plates of the movement and carrying a guard wire and a guard-operating wire, and combined with a friction-member for holding it in its respective guard and clearance positions. 90

My invention further consists in a chime-clock of the character described, having certain details of construction as will be hereinafter described and pointed out in the claims. 95

In carrying out my invention, as herein shown, my invention is embodied in a chime-clock having a front movement-plate 10, an intermediate movement-plate 11 and a rear movement-plate 12, united and spaced apart in the usual manner by pillars 13 and providing a front train-space 14, in which the time-and-strike-trains are located, and a rear train-space 15 in which the chime-train and other features of the chime-mechanism are located. As shown, the time-and-strike-trains, which may be of any standard construction, have been omitted as unnecessary for the disclosure of my invention, and for clarity, with the exception of the center- 100

arbor 16 of the time-train, and the chime-releasing star-wheel 17, which is mounted on the said arbor for rotation therewith, and which is the operating connection between the time-train and the chime-train. I would have it understood, however, that my present invention is also applicable to two plate-movements.

As herein shown, my frictionally-controlled, chime-correcting unit consists of a rocking-arbor 18 journaled at its ends in the intermediate movement-plate 11 and rear movement-plate 12 and carrying a wire guard 19 and a guard-operating wire 20. A spring friction-washer 21 interposed between a shoulder on the rear end of the arbor 18 and the rear movement-plate 12 provides for the friction required for sustaining the unit in either of its two positions, i. e., its guard position and its clearance position.

The wire guard 19 of the unit is bent rearwardly and flattened to form a guard-finger 22, which is moved into and out of the path of a guard-pin 23 located in the fourth wheel 24 of the chime-train, which may be of any approved construction. The guard-operating wire 20 of the unit is formed at its lower end with an upwardly-inclined hook 25 co-acting with a chime-correcting pin 26 in a chime-count disk 27 on the arbor 28 of the third wheel 29 of the chime-train. The rocking-arbor 18 also carries a short upstanding wire 30 having its upper end bent forwardly to form a finger 31 extending into a small hole 32 in the plate 11 and engaging with the opposite walls thereof to limit the rocking movement of the arbor 18 and hence the movement of the wires 19 and 20 carried thereby. The chime-correcting unit thus described operates in conjunction with the lock-work of the chime-mechanism, which it is unnecessary to describe in detail, except insofar as such co-action is concerned.

As shown, the lock-work of the chime-mechanism comprises a rocking-arbor 33 located below the rocking-arbor 18 and similarly journaled at its ends in the plates 11 and 12. The said arbor 33, which, for convenience, may be called the warning-arbor, carries at its inner end a wire warning-hook 34, the upturned end 35 of which co-acts with a warning-pin 36 in the fifth wheel 37 of the chime-train, the said wheel being mounted upon the fifth wheel shaft 38 thereof. The said shaft 38 also mounts a chime-locking disk 39 having a locking-notch 40 entered by the upturned end 41 of a locking-wire 42 mounted upon a rocking count-hook arbor 43 journaled between the plates 11 and 12 and carrying a wire count-hook 44, the lower end of which is bent forwardly to form a finger 45 successively entering the four notches 46 of the count-wheel 27. These notches 46 are differentially spaced to divide

the periphery of the said wheel 27 into four dwells upon which the finger 45 rides during the chiming of the clock, these dwells consisting of the quarter-hour dwell 47, the half-hour dwell 48, the three-quarter hour dwell 49 and the full-hour dwell 50. The count-hook 44 is lifted out of engagement with the said notches 46 in the count-wheel 27 for releasing the same, by means of the forwardly-bent end 51 of a lifting-wire 52 mounted in the warning-arbor 33. Such lifting of the count-hook 44, by the wire 52, not only raises the end 45 of the count-hook 44 out of the particular notch 46 of the count-wheel 27 with which it may be engaged at any given time, but also depresses the locking-wire 42, so as to disengage its end 41 from the locking-notch 40 in the locking-disk 39 aforesaid, whereby the chime-train is unlocked for the warning of the chime-train, which, for this warning purpose, starts up and runs until the warning-pin 36 in the fifth wheel 37 has been brought into engagement with the warning-hook 35, which was lifted into the path of the said pin approximately concurrently with the unlocking of the train by the depression of the locking-wire 42 and the lifting of the count-hook 44 out of one of the notches 46 in the count-wheel 27, by the action of the lifting-wire 52. The above described action is common in clocks of this type, the warning of the mechanism closely preceding the unlocking of the train. For rocking the warning-arbor 33 to raise the lifting-wire 52 to effect the warning of the mechanism, as above described, the said arbor is provided with a sheet-metal lifting-lever 53 secured to the forward end of the arbor and extending into position to co-act with the teeth of the star-wheel 17 mounted upon the center arbor 16. This star-wheel is formed with four equidistant teeth 54, 55, 56 and 57 respectively corresponding to the quarter hour, half hour, three-quarter hour, and full hour chiming periods, the tooth 57 being made longer than the other three teeth, so that once an hour, in addition to unlocking and warning the chime-train, it will perform the additional function of operating the chime-correcting unit, as will be hereinafter described.

Having now described my invention, I will proceed to set forth the mode of operation thereof.

In its normal operation, the clock chimes every quarter hour, the chime-correcting unit, constituting the salient feature of my present invention, remaining entirely inactive with the exception that just before the chime-train completes chiming on the third quarter of the hour, the pin 26 in the count-wheel 27 engages the upturned end 25 of the guard-operating hook 20, thus depressing the guard-finger 22 of the guard 19 into the path of the guard-pin 23 in the fourth wheel

24 of the chime-train. Toward the end of the ensuing fifteen minutes, the long tooth 57 of the star-wheel 17 will be brought into play, with the effect of warning the chime-train in the same manner in which it is warned by the three shorter teeth 54, 55 and 56 of the said wheel. More than this, and on account of the extra length of the tooth 57, it lifts the lever 53 enough more 10 than the same is lifted by the said shorter teeth of the wheel to additionally lift the lever 52 enough to cause the same to lift the guard 19 sufficiently to lift its finger 22 out of the path of the guard-pin 23, against the 15 tension of the friction-spring 21. Now, when the said lever 53 drops off the long tooth 57 of the star-wheel 17, the chime-train starts and chimes the hour. This cycle of operations is repeated so long as the time- and 20 chime-mechanisms are in consonance, the chime-correcting unit being idly moved against the tension of its friction spring into its guard position at the completion of the chiming on the third quarter of the hour, 25 and returned against the tension of its friction spring, into its clearance position near the conclusion of the next quarter-hour period.

On the other hand, supposing that the 30 time- and chime-mechanisms have been dislocated or asynchronized for one reason or other, it does not matter what, so that the quarter-hour chiming does not correspond to the quarter-hour periods indicated by the 35 time-mechanism, it may be assumed that the chime-mechanism has fallen out of synchronism with the time-mechanism, as illustrated in Figs. 1 and 2, in which the star-wheel 17, which represents the time-train, is 40 shown in the position calling for chiming the quarter hour, whereas, the count-wheel of the chime-mechanism is in the position for next chiming the full hour. In this situation, the guard of the time-correcting unit 45 is necessarily in its guarding position, with its guard finger 22 in the path of the guard-pin 23 in the fourth wheel 24 of the chime-mechanism, so that when the time-mechanism operates on the hour to release the 50 chime-mechanism, the same is thus restrained by the guard finger of the guard, which remains in this position of preventing the operation of the chime-train until the time-train has, so to speak, 55 "caught up" with the chime-train and brought the long tooth 57 of the star-wheel 17 into play for effecting the lifting, through an extra lifting of the levers 53 and 52 of the guard 19, against the friction of its spring 60 21, into its clearance position, in which its finger 22 is out of the path of the guard-pin 23 in the fourth wheel 24 of the chime-train, as indicated in Fig. 3. When now the lever 53 drops off the long tooth 57 of the wheel 65 17, the chime-mechanism will be released for

chiming the hour, and the chime- and time-mechanism, having thus been synchronized, will continue to act co-ordinately until they are, through accident or carelessness, asynchronized, after which, without any action 70 on the part of the user of the clock, but entirely automatically, they will be re-synchronized, or re-co-ordinated on the hour, as above described. It will thus be seen that with my improved chime-correcting unit, the 75 chime may conceivably be sounded three successive times out of consonance with the time indicated by the hands of the clock, but no more, depending upon the time within the hour when the chime-train and the time-train fell out of synchronism, but, in any event, the hour cannot be chimed out of time. In the clock structure herein shown, I have chosen and preferably choose to automatically re-synchronize the chime- and time-mechanisms on the hour, but, if preferred, the clock may be set without any change of principle or structure to re-synchronize the chime- and time-mechanisms on the first, 80 second or third quarters of the hour, this 85 being done by merely changing the position of the star-wheel on the center arbor with a corresponding re-positioning of the pin 26 in the count-wheel 27.

I claim:

1. A chime clock having time- and chime-trains, and a frictionally-controlled chime-correcting unit moved into its guard position for preventing the chime from sounding by the chime-train, and into its clearance position under the control of the time-train, the said unit comprising a rocking-arbor journaled at its ends in plates of the movement and carrying a guard-member and a guard-operating member mounted upon it between 100 its ends, so as to be positioned between the plates in which they are journaled for co-action, respectively, with the chime and time trains of the clock.

2. A chime clock having time- and chime-trains, and a frictionally-controlled chime-correcting unit moved into its guard position by the chime-train for preventing the chime from sounding, and into its clearance position under the control of the time-train, the said unit comprising a rocking-arbor journaled at its respective ends in plates of the movement and carrying a wire-guard and a guard-operating wire mounted upon it between its ends so as to be positioned between the said plates for co-action, respectively, with the chime and time trains of the clock.

3. A chime clock having time- and chime-trains, a frictionally-controlled chime-correcting unit consisting of a rocking-arbor journaled in plates of the clock and having a wire guard and a guard-operating wire, a warning-arbor also journaled between the said plates and provided with a 125 130

- lifting wire co-acting with the guard of the said unit, a count-hook arbor journaled between the said plates, and carrying a count-hook operated by the said lifting-wire, a star-wheel driven by the time-mechanism and having an elongated tooth, and a lifting lever carried by the warning-arbor and operated by the long tooth of the star-wheel, whereby the said guard is moved into its guard position for preventing the chime from sounding by the chime-train, and into its clearance position under the control of the time-train and held by friction in its respective positions.
- 15 4. In a chime clock, the combination with front, rear and intermediate movement-plates providing a train-space for the time- and strike-trains, and a separate space for the chime mechanism, a chime mechanism lo-

cated in the said chime mechanism space, 20 and a frictionally-controlled, chime-correcting unit comprising an arbor journaled between the said intermediate and rear movement-plates, and carrying a wire guard and a guard-operating wire, the said unit 25 being moved into its guard position for preventing the chime from sounding by the chime-train and into its clearance position under the control of the time-train and held by friction in its respective positions. 30

In testimony whereof, I have signed this specification in the presence of two subscribing witnesses.

FREDERICK WEHINGER.
